United States Patent Office

Des. 177,958
Patented June 12, 1956

177,958

SHORTS OR THE LIKE

William Bender, New York, N. Y.

Application September 27, 1954, Serial No. 32,441

Term of patent 3½ years

(Cl. D3—17)

Fig. 1.

Fig. 2.

Fig. 1 is a front elevational view of shorts or the like, showing my new design.

Fig. 2 is a rear elevational view thereof.

I claim:

The ornamental design for shorts or the like, substantially as shown.
